UNITED STATES PATENT OFFICE.

LUTHER G. ALLEN, OF BROOKLYN, NEW YORK.

DESIGN FOR A LAVATORY OR WASHSTAND.

45,283.

Specification for Design.

Patented Feb. 24, 1914.

Application filed December 15, 1913. Serial No. 806,922. Term of patent 3½ years.

● *To all whom it may concern:*

Be it known that I, LUTHER G. ALLEN, a citizen of the United States, and a resident of Brooklyn, Kings county, New York, have invented a new, original, and ornamental Design for a Lavatory or Washstand, of which the following is a specification, reference being had to the accompanying drawing, in which—

Figure 1, is a front elevation of the lavatory or washstand, and Fig. 2, is a perspective view looking toward the right-hand side of the same.

I claim:

The ornamental design for a lavatory or washstand, substantially as described and as shown in the accompanying drawing.

In testimony whereof, I have signed my name to this specification, in the presence of two subscribing witnesses.

LUTHER G. ALLEN.

Witnesses:

ANDREW COCHRAN,
KENDRICK H. NICHOLS.
